(Cl. D81—10)

To all whom it may concern:

Be it known that I, Carl Reynolds, Jr., a citizen of the United States, residing at Detroit, in the county of Wayne and State of Michigan, have invented a new, original, and ornamental Design for an Electrical Heating Apparatus, of which the following is a specification, reference being had to the accompanying drawing, forming part therof.

Fig. 1 is a perspective view of an electrical heating apparatus, showing my new design, and showing particularly the top, the front and one side thereof; and

Fig. 2 is a rear elevation thereof.

I claim:

The ornamental design for an electrical heating apparatus, as shown.

CARL REYNOLDS, JR.
